SOAP-DISPENSING BAG

Howard A. Miller, Greenback, Tenn.

Application March 21, 1949, Serial No. 82,501

1 Claim. (Cl. 15—122)

1

This invention relates to soap holders and, in particular, to soap bags.

One object of this invention is to provide a soap bag of open mesh material so constructed as to permit easy insertion of the soap while preventing its accidental escape from the bag.

Another object of this invention is to provide a soap bag of open mesh material which is easily manufactured by mass production methods at low cost of production.

Another object is to provide a soap bag of open mesh material wherein the strands thereof are coated with a rubber-like material such as natural or synthetic rubber or rubber-like plastic and thereby rendered impervious to either soap, water or dirt, thus preventing deterioration of the fibres and lengthening the life of the bag as well as rendering it smooth to the touch.

Another object is to provide a soap bag of open mesh material so constructed as to be easily held in the hand and having a pocket for receiving the finger tips so that it will not easily slip out of the grasp of the user.

Another object is to provide a soap bag of open mesh material which may be used to receive soap scraps or broken pieces which would otherwise be wasted.

In the drawing:

Figure 1 is a front elevation of the soap bag of this invention, with the bag open to receive the soap, prior to folding over the closure flap;

Figure 2 is a top plan view of the soap bag shown in Figure 1, with the mouth of the bag open to receive the soap;

Figure 3 is a vertical section along the line 3—3 of Figure 1, showing the location of the soap retention flap and the closure flap respectively;

Figure 4 is a diagrammatic perspective view showing how the flaps are folded over the ends of the sheet of mesh material prior to uniting the edges thereof to form the bag;

Figure 5 is a diagrammatic vertical cross section similar to Figure 3, showing the position of the soap retention flap before the closure flap has been folded over;

Figure 6 is a view similar to Figure 5, taken after the closure flap has been folded over the mouth of the bag to close the bag and provide a finger pocket; and

Figure 7 is a perspective view showing the soap bag in use with the fingers inserted in the finger pocket formed by the folded over closure flap.

Referring to the drawings in detail, Figure 1 shows a soap bag, generally designated 10, ac-

2

cording to one form of the invention in the form of an envelope of loosely-woven material having front and rear walls 11 and 12 (Figure 3). The front wall 11, which is the wall eventually engaged by the fingers and palm of the hand, has an inwardly turned soap-retention flap 13 which serves as a trap to prevent the soap from coming out when it has once been inserted. Similarly, the rear wall 12 is provided with an outwardly-turned closure flap 14 which, as explained below, is turned inside out while being pulled over the mouth 15 of the bag 10 after the soap S has been inserted in the soap chamber 16 thereof.

15 The soap bag 10 is formed of open mesh material such as netting having threads or strands 17 of suitable material such as cotton, paper, nylon or other material used for making threads or cords. The material of the threads 17 is 20 coated with rubber-like material such as natural or synthetic rubber or rubber-like plastic. This coating protects the threads by resisting the entrance of water or grease and prolongs the life of the threads. It also makes it smooth to 25 the touch, and impervious to the soap itself so that the threads will not become slimy. The threads 17 of the open mesh material are coated with the rubber-like material either in the sheet 30 form before the material is cut into strips, or the entire bag may be coated in this manner at any stage of its manufacture.

The walls 11 and 12 are secured to one another along inwardly turned seams 18 and 19, the seams 18 and 19 being of four thicknesses in the 35 upper portion of the bag where the side edges 20 and 21 of the turned over flaps 13 and 14 are combined with the seams. The seams 18 and 19 are preferably stitched together and then sealed by a suitable sealing compound, such as the rubber-like material previously mentioned.

In the manufacture of the soap bag 10, an elongated rectangular strip of mesh material such as netting is cut of sufficient length to provide a bag of the desired depth and with the flaps 13 and 14 of the desired width. In other words, the length of the strip would be approximately equal to the combined heights of the side walls 11 and 12 (Figure 3) increased by the combined depths 40 of the flaps 13 and 14. The opposite end portions of the strip are bent over and back upon the strip in the same direction, as shown in Figure 3, at the bending lines 22 and 23 respectively. With the flaps thus bent over, upon the strip, the 45 strip itself is bent at its midportion along the 50

bending lines 24 to bring the side edges of the side walls 11 and 12 together.

These side edges are then preferably stitched together and the seams sealed by means of a sealing compound such as natural or synthetic rubber or rubber-like plastic, the sealing compound extending laterally to the desired width of the seam, for example, one quarter inch. The bag is now inside out with the seams projecting outward, hence it is next turned outside in to cause the seams to be on the inside of the bag facing inward as shown in Figure 2.

The diagrammatic perspective view in Figure 4 shows the bag after the flaps 13 and 14 have been folded over, but before the side edges have been united and the bag turned outside in to place the seams 18 and 19 on the inside as shown in Figure 2. After this has been done, the bag is ready for the insertion of the soap S.

In the use of the soap bag 10 of this invention, let it be assumed that the mouth 15 of the bag is open, as shown in Figures 1, 2 and 3 and 5. The soap S, if in the form of a cake or the pieces thereof, are inserted through the mouth 15 of the bag and pushed down into the chamber 16 in the interior thereof. The lower edge 25 of the retention flap 13 is then pulled upward over the top of the cake of soap S or over the pieces thereof until these lie within the space 26 (Figure 5) and the retention flap 13 overlies the soap S. The user now grasps the lower edge 27 of the closure flap 14 (Figures 3 and 5) and pulls the flap 14 inside out over the mouth 15 of the bag, causing it to assume the position of Figure 6 overlying and engaging the forward wall 11 of the bag. The soap S is now doubly retained or trapped in the bag by the flaps 13 and 14.

The user, may, of course, grasp the bag with the soap inside it in any convenient way. Figure 7, however, shows a convenient way of grasping the bag so that it will not slip out of the hand. In so doing, the user inserts the tips of his fingers into the pocket 28 (Figure 6) between the flap 14 and the wall 11, and grasps the opposite wall 12 with his thumb. The device may then be used to work up a lather by shaking it to and fro. The soap cannot escape from the bag and even small pieces are prevented from escaping because of the mesh construction of the bag. At the same time, water can flow into and out of the bag freely in order to dissolve the soap and create a lather. It can be used for bath, dishes, laundry, cleaning, or wherever soap is used.

In addition to shaking the soap bag to produce a lather, as described above, this lather can also be produced by rubbing the soap bag against the article to be cleaned. The open mesh construction of the present invention also enables the soap bag to be hung up and allowed to dry out after use. The open mesh construction enables the air to circulate freely around the soap

during the drying out operation, thereby preventing the soap from becoming soft and useless and accordingly saving soap. In contrast to this, soap left in an ordinary soap dish is often left standing in water in the bottom of the dish. This not only prevents drying out of the soap but renders it jelly-like and wastes soap.

What I claim is:

A soap bag comprising an envelope of porous material having front and rear walls secured to one another in approximately parallel relationship and closed along their bottom and side edges, said front and rear walls having upper edges spaced apart from one another to form an open mouth for said envelope, an inner flap extending downwardly from the upper edge of said front wall into the interior of said envelope partway along the inner side of said front wall, the upper edge and side edges of said inner flap being secured to and closed along said upper edge and said side edges respectively of said front wall and cooperating with said front wall to form an inner soap-retaining pocket, the lower edge of said inner flap being separated from said front and rear walls to form a downwardly open mouth for said inner pocket, and an outer flap extending from the upper edge of said rear wall downwardly partway along the outer side of said rear wall, the upper edge and side edges of said outer flap being secured to and closed along said upper edge and side edges respectively of said rear wall and cooperating with said rear wall to form an outer closure pocket, the lower edge of said outer flap being separated from said rear wall to form a downwardly open mouth for said outer pocket, whereby said outer flap is foldable inside out over said open mouth of said envelope to close said envelope mouth by moving said lower edge of said outer flap upwardly over the edges of said open mouth and then downwardly along the outer surface of said front wall.
